UNITED STATES PATENT OFFICE

JAY BENJAMIN HALL, OF EUGENE, OREGON

SNOWPLOW

Application filed May 17, 1929. Serial No. 363,792.

This invention relates to certain new and useful improvements in snow plows especially designed for the removal of snow from roads and highways as well as railroad tracks 5 and has for one of its objects the gathering of snow and ice for distant discharge.

The primary object of the invention is to provide a snow plow having a shovel-like casing positioned forwardly of and attached to 10 a tractor or other propelling mechanism with rotatable blades or shovels disposed at the forward open side of the casing for cutting ice and snow and for gathering the same into the casing for discharge by a fan blower 15 through a conduit to a distant point.

A further object of the invention is to provide a snow plow of the above type wherein in the rotatable shovel and fan blower are operatively engaged with the power plant of 20 the tractor with means interposed therebetween for varying the speed of rotation of the fan and shovel.

Another important object of the invention is to provide a snow plow as before set forth 25 wherein the rotatable shovels are supported on vertical shafts journaled in the forward open side of the casing, the shovels travelling in a path forwardly of the casing for breaking the snow and ice before the casing moves 30 into contact therewith for the purpose of offering the least resistance possible to the forward travel of the apparatus.

A still further object of this invention is to provide a snow plow that is vertically 35 shiftable to be separated from the ground line permitting transportation of the machine when out of use and also compensating for unevenness in line of travel as well as escaping abutments such as stones and the 40 like.

With the above and other objects in view that will become apparent as the nature of the invention is better understood, the same consists in the novel form, combination and 45 arrangement of parts hereinafter more fully described, shown in the accompanying drawings and claimed.

In the drawings:—

Figure 1 is a fragmentary top plan view, 50 partly broken away and shown in section of

the snow plow with the gathering and cutting shovels located at the forward open side of the scoop or shovel-like casing.

Figure 2 is a front elevational view of the snow plow showing the snow and ice cutting 55 and gathering shovel extending across the open front side of the casing and the operating mechanism for the shaft carrying the shovel;

Figure 3 is a side elevational view of the snow plow;

Figure 4 is a detail cross-sectional view through one of the shovel supporting shafts showing the disk enlargement carried thereby and the snow and ice cutting and gathering shovels pivoted thereon; and 65

Figure 5 is a fragmentary elevational view of one of the shafts with the shovel arms pivoted thereon.

The snow plow comprises a shovel casing 70 located forward of and attached to a propelling device such as a tractor in a manner to be later described, the casing being of trapezoidal formation in plan view and comprising rearwardly converging top and bottom walls 75

1 and 2, rearwardly converging side walls 3 and a rear wall 4, all of said walls being secured together at their meeting edges in any suitable manner, such as by angle irons 5 that are riveted thereto as at 6, the casing being 80 completely open at its forward side at 7 as shown in Figures 1 and 2. A front shoe or runner bar 8 of the form best illustrated in

Figure 3 extends across the forward edge of the lower wall 2 of the casing and carries 85 rearwardly extending runner arms 9, perpendicularly bent as at 10 and secured to the adjacent side walls 3, or wheels, preferably flanged wheels, may be used in place of the runner arms 9. A bar or rod 11 is riveted or otherwise secured as at 12 to the side walls 3 of the casing and extend rearwardly for pivotal attachment to a tractor, not shown. Control lines in the form of cables or the like are shown at 13 are attached as at 14 at their 90 forward ends to the forward upper corners of the side walls 3 and are controlled from the tractor for raising and lowering the casing

95 relatively to the ground line 15 so that the casing may be elevated when the plow is 100

being transported from one place to another and also to escape abutments such as stones and the like.

A plurality of vertical shafts 17 are journaled across the front opening 7 of the casing, the same being supported at the lower ends in suitable bearings carried by the bottom wall 2 of the casing while the upper ends thereof are journaled in a cross bar 16 supported at its ends on the side walls 3 at points spaced below the top wall 1, the shafts 17 being equidistantly spaced from each other and while four of such shafts are illustrated, it is to be understood that any preferred number may be employed. As shown more clearly in Figures 2, 4 and 5, each shaft 17 has a plurality of spaced disk blocks 18 keyed thereon as at 19 with the blocks 18 of adjacent shafts being located in different horizontal planes. A plurality of blades or shovel arms 20 of curved formation in plan view are pivotally mounted at their inner ends as at 21 upon the upper side of the disk block 18, preferably four shovel arms 20 being associated with each block, the shovel arms on adjacent shafts overlapping each other in vertically spaced relation as shown in Figure 2. The shafts 17 are disposed with relation to the forward side of the casing so that the shovel arms 20 project beyond the casing as illustrated in Figures 1 and 2 for breaking down a bank of ice and snow forwardly of the casing.

The operating mechanism for rotating the shafts 17 includes a drive shaft 22 leading from the power plant of the tractor and extending into the transmission housing 23, the speed gears of which are changed by the control rod 24 extending rearwardly to the tractor. The shaft 25 extending perpendicularly from the transmission housing 23 and driven by the gear mechanism therein extends into a gear box 26 at its upper end and is provided with a bevel gear 27 that meshes with a bevel gear 28 upon the forwardly projecting shaft 29 that extends through a slotted opening 30 in the top wall 1 of the casing, the same being supported at its forward end by a suitable bearing 31 and provided with a bevel gear 32 upon its terminal end. A horizontal shaft 33 is supported at intervals in bearings on the brackets 34 mounted upon the bar 16 and said shaft 33 has fixed thereto a series of bevelled pinions 35 that mesh with bevel gears 36 fixed to the upper ends of the shaft 17 above the bar 16. The bevel gear 32 upon the shaft 29 meshes with a bevel gear 37 fixed to the shaft 33 as shown in Figures 1 and 2 for the transmission of power from the shaft 29 to the several shafts 17 carrying the shovel arms 20.

The transmission housing 23 is supported centrally of the rear wall 4 of the casing as shown in Figures 1 and 3 and a shaft 38 projects through the rear wall 4 into the casing to be driven by the gear mechanism in the

housing 23. A fan blower or wheel comprising blade arms 39 is fixed to the shaft 38 adjacent the casing wall 4 and is adapted to force snow and ice gathered in the casing by the shovel arms 20 through an opening in the top wall 1 into the discharge conduit 40 outletting at a distant point. The speed of rotation of the fan wheel 39 and gear mechanism in the transmission housing 23 may be varied proportionately to the amount of snow and ice collected in the casing.

From the above detailed description of the invention, it is believed that the construction and operation will at once be apparent, it being noted that the snow plow is positioned forwardly of a propelling device such as a tractor and supported on the tractor by the rearwardly extending bars 11. The cables 13 are operated for raising and lowering the casing as previously described, while the shovel arms 20 projecting forwardly of the casing as illustrated in Figures 1 and 3, break down a bank of ice and snow preparatory to contact therewith of the casing so that forward movement of the snow plow is substantially unimpeded. The shovel arms 20 extend completely across the open forward side of the casing as illustrated in Figure 2, the shovel arms upon adjacent shafts being in different horizontal planes, in staggered relation, and overlapping each other in their movement for the more effective cutting and gathering of snow and ice. The shovel arms 20 are pivotally supported upon the disk blocks 18 and when the shafts 17 are rotated through the chain of gear mechanism described, the shovel arms are thrown outwardly to assume the position shown in Figure 4 and in their movements describe a circle, one side of which is forwardly of the casing, the shovel arms throwing the snow and ice onto the fan wheel 39 which in turn delivers the same to the outlet conduit 40 for distant discharge. The speed of rotation of the shovel arms 20 and fan wheel 39 is regulated by the speed gear mechanism in the transmission housing 23 under control of the operating rod 24.

While there is herein shown and described the preferred embodiment of the invention, it is nevertheless to be understood that minor changes may be made therein, without departing from the spirit and scope of the invention as claimed.

I claim:—

1. A snow plow adapted for mounting on the front end of propelling mechanism and comprising a shovel-like casing open at its forward side, snow gathering shovels extending across the open side of the casing including disk blocks and shovel blades pivoted at their inner ends to swing in planes perpendicular to the axes of said disk blocks; and a fan blower in the casing for conveying gathered snow to a distant point for discharge.

2. A snow plow adapted for mounting on the front end of propelling mechanism and comprising a shovel-like casing open at its forward side, snow gathering shovels extending across the open side of the casing including disk blocks and shovel blades pivoted at their inner ends to swing in planes perpendicular to the axes of said disk blocks, and a fan blower in the casing for conveying gathered snow to a distant point for discharge, the shovels including radial shovel arms movable circularly in a horizontal plane and projecting forwardly of the casing. 70
- 10 3. A snow plow adapted for mounting on the front end of propelling mechanism and comprising a shovel-like casing open at its forward side, snow gathering shovels extending across the open side of the casing including disk blocks and shovel blades pivoted at their inner ends to swing in planes perpendicular to the axes of said disk blocks, a fan blower in the casing for conveying gathered snow to a distant point for discharge, vertical shafts carrying the shovels, operating means for the shafts in communication with the power plant of the propelling mechanism. 75
- 15 4. A snow plow adapted for mounting on the front end of propelling mechanism and comprising a shovel-like casing open at its forward side, snow gathering shovels extending across the open side of the casing, a fan blower in the casing for conveying gathered snow to a distant point for discharge, the shovels including radial shovel arms movable circularly in horizontal planes and projecting forwardly of the casing, vertical shafts carrying the shovels, hubs on said shafts having the inner ends of the shovels pivoted thereto to swing in planes perpendicular to the axes of said shafts, and operating means for the shafts in communication with the power plant of the propelling mechanism. 80
- 20 5. A snow plow adapted for mounting on the front end of propelling mechanism and comprising a shovel-like casing open at its forward side, snow gathering shovels extending across the open side of the casing, a fan blower in the casing for conveying gathered snow to a distant point for discharge, vertical shafts carrying the shovels, hubs on said shafts having the inner ends of the shovels pivoted thereto to swing in planes perpendicular to the axes of said shafts, and operating means for the shafts in communication with the power plant of the propelling mechanism. 85
- 25 6. A snow plow adapted for mounting on the front end of propelling mechanism and comprising a shovel-like casing open at its forward side, snow gathering shovels extending across the open side of the casing, a fan blower in the casing for conveying gathered snow to a distant point for discharge, the shovels including radial shovel arms movable circularly in horizontal planes and projecting forwardly of the casing, vertical shafts carrying the shovels, operating means for the shafts in communication with the power plant of the propelling mechanism, the connection between the shovel arms and shafts including disk blocks fixed to the shafts, and the shovel arms being pivoted at their inner ends to the disk blocks. 90
- 30 7. A snow plow adapted for mounting on the front end of propelling mechanism and comprising a shovel-like casing open at its forward side, snow gathering shovels extending across the open side of the casing, a fan blower in the casing for conveying gathered snow to a distant point for discharge, vertical shafts carrying the shovels, operating means for the shafts in communication with the power plant of the propelling mechanism, the connection between the shovel arms and shafts including disk blocks fixed to the shafts, and the shovel arms being pivoted at their inner ends to the disk blocks. 95
- 35 8. A snow plow adapted for mounting on the front end of propelling mechanism and comprising a shovel-like casing open at its forward side, snow gathering shovels extending across the open side of the casing, a fan blower in the casing for conveying gathered snow to a distant point for discharge, the shovels including radial shovel arms movable circularly in horizontal planes and projecting forwardly of the casing, vertical shafts carrying the shovels, operating means for the shafts in communication with the power plant of the propelling mechanism, the connection between the shovel arms and shafts including disk blocks fixed to the shafts and the shovel arms being pivoted at their inner ends to the disk blocks. 100
- 40 9. A snow plow adapted for mounting on the front end of propelling mechanism and comprising a shovel-like casing open at its forward side, snow gathering shovels extending across the open side of the casing, a fan blower in the casing for conveying gathered snow to a distant point for discharge, vertical shafts carrying the shovels, hubs on said shafts having the inner ends of the shovels pivoted thereto to swing in planes perpendicular to the axes of said shafts, operating means for the shafts in communication with the power plant of the propelling mechanism, the operating means including a horizontal shaft journaled above the vertical shafts, gear connections between the horizontal and vertical shafts, and speed change gearing in communication with the horizontal shaft. 110
- 45 10. A snow plow adapted for mounting on the front end of propelling mechanism and comprising a shovel-like casing open at its forward side, snow gathering shovels ex- 115
- 50 120
- 55 125
- 60 130

tending across the open side of the casing, a fan blower in the casing for conveying gathered snow to a distant point for discharge, the shovels including radial shovel arms
6 movable circularly in horizontal planes and projecting forwardly of the casing, vertical shafts for carrying the shovels, hubs on said shafts having the inner ends of the shovels pivoted thereto to swing in planes perpendicular to the axes of said shafts, operating means for the shafts in communication with the power plant of the propelling mechanism, the operating means including a horizontal shaft journaled above the vertical shafts, gear connections between the horizontal and vertical shafts, and speed change gearing in communication with the horizontal shaft.

In testimony whereof I affix my signature.
